(57) **CLAIM**

The ornamental design for a trivet, as shown and described.

DESCRIPTION

FIG. 1 is a perspective view of a trivet showing my new design;

FIG. 2 is a top view of the trivet;

FIG. 3 is a front view of the trivet, the rear view being a mirror image thereof;

FIG. 4 is a right side view of the trivet, the left side view being the same;

FIG. 5 is a bottom view of the trivet;

FIG. 6 is a cross-sectional view of wire used to form the trivet; and,

FIG. 7 is a perspective view showing a second embodiment of my new design, all views being the same as the first embodiment except the cross-section of the wire which is round or slightly oval.

The broken lines in the drawing illustrate environmental matter and form no part of the claimed design.
